United States Patent Office

Des. 212,949
Patented Dec. 17, 1968

212,949

DENTAL INSTRUMENT SUPPORTING UNIT

Charles M. Weiss and David Harold Linn, New York,
N.Y., assignors to S. S. White Company, Philadelphia,
Pa., a corporation of Pennsylvania

Original design application May 1, 1967, Ser. No. 6,906,
now Patent No. 210,126, dated Feb. 13, 1968. Divided
and this application Sept. 1, 1967, Ser. No. 8,563

Term of patent 14 years

(Cl. D24—1)

FIG. 1

FIG. 2

FIGURE 1 is a perspective view of a dental instrument supporting unit, showing our new design;

FIGURE 2 is a side elevational view thereof.

Those sides of the unit not shown are substantially plain and unornamented.

This is a division of design application Serial No. 6,906, filed May 1, 1967 and now Patent No. D.210,126.

We claim:

The ornamental design for a dental instrument supporting unit, as shown and described.
